UNITED STATES PATENT OFFICE.

MARTIN L. WILLIAMS, OF SOUTH BEND, INDIANA.

INTERNAL-COMBUSTION ENGINE.

972,966.

Specification of Letters Patent. Patented Oct. 18, 1910.

Application filed January 21, 1907. Serial No. 353,223.

To all whom it may concern:

Be it known that I, MARTIN L. WILLIAMS, a citizen of the United States, residing at South Bend, St. Joseph county, State of Indiana, have invented certain new and useful Improvements in Internal-Combustion Engines, of which the following is a specification.

This invention relates to improvements in internal-combustion engines, and refers more specially to an improved multiple cylinder two-cycle engine.

Among the salient objects of the invention are to provide an engine in which each power cylinder has associated therewith a compression cylinder, and the pistons of each associated pair of cylinders are so timed as to coöperate in a peculiar and novel manner; to provide a construction in which the main parts of the engine rotate, and the rotation of the cylinders is made to effect a suitably timed movement of the pistons of the compression cylinders through the connections of the latter with relatively fixed parts, to provide a construction in which a centrally disposed crank-easing constitutes a gas-supply chamber common to the intakes of all of the compression cylinders; to provide a construction in which the pistons of both the power and compression cylinders constitute the movable members of the valves which control the motive-fluid passages leading into and out of said cylinders; to provide a construction in which the out stroke of the piston of each compression cylinder creates a partial vacuum in said cylinder which, when the intake port is opened, induces the prompt filling of the cylinder with a fresh charge; to provide a construction in which the piston-rods of the several power pistons are connected with a single common crank, the cylinders are radially and equiangularly disposed, and the firing is effected at a definite point in the rotation of the group, whereby the propelling impulses occur in regular succession and are uniformly effective; and, in general, to provide improvements in the arrangement and construction of the parts contributing to the production of a simple, economically constructed, and efficient engine.

The invention consists in the matters hereinafter described and more particularly pointed out in the appended claims; and will be more readily understood by reference to the accompanying drawings, in which:

Figure 1 is a partly vertical section, on broken line I—I of Fig. 3, of a preferred embodiment of the invention; Fig. 1^a is a detail view of one of the circuit-closing members of the ignition system; Fig. 2 is a broken-away vertical section taken on broken line II—II of Fig. 1; Fig. 3 is a vertical section on broken line III—III of Fig. 1, omitting the fixed frame; Fig. 4 is a detached view of the mechanism for actuating the compression or auxiliary pistons; Fig. 5 is a vertical section of an engine in which the arrangement of the compression cylinders is modified; and Fig. 6 is a vertical section on broken line VI—VI of Fig. 5.

Referring first to Figs. 1 to 4 inclusive, illustrating the preferred construction: 1 is a suitable base or bed-plate, provided with two bearing-stands 2, 2, which support the non-rotatable crank-shaft 3, which is keyed to its bearings as shown at 4, 4. All other parts of the engine revolve about this shaft 3, with the exception of a fixed cam member 29, to be described.

The principal frame members of the revolute part of the engine are, the crank-casing 6, the compression-cylinder casting 15, and the cam-chamber 8; said several castings being bolted together as shown. These members are mounted on the shaft 3 through the medium of several antifriction bearings 9, 10, 10. Preferably the two latter are positioned at or near the respective sides of the crank-casing, and the third bearing, at or close to the opposite end of the engine. The power may be taken from the engine at any of several different points: for example a pulley surface is provided at 11, and if a larger pulley be desired such pulley may be secured to the part 11 or to the end face of the chamber 8. As shown, a sprocket-wheel 12 is keyed upon the projecting portion 11.

The power cylinders, 14, are bolted to the crank-casing 6, extend radially therefrom, are equidistant from each other, and are preferably odd in number, as shown. Associated with each power cylinder is a compression cylinder 15, in which is provided a piston for forcing the gas into the associated power cylinder as hereinafter described. In the preferred construction these compression cylinders are arranged parallel to and equidistant from the shaft 3, and are cast in one piece, which includes a transverse web 16, an end-plate 17 secured to the power cylinders 14, and the hub-like portion

18 which holds one of the bearings 10. However, these cylinders are not necessarily made integral with one another.

In alinement with the power pistons 19, 5 the shaft 3 is provided with a power crank 20, which is connected to said pistons by respective piston-rods 21, all of equal lengths. The pitman-heads (or crank-boxes) 22 need not be offset nor staggered, as 10 they may be connected to the crank either in the manner shown in Fig. 2 or that shown in Fig. 5, whereby the piston-rods 21 will all be in the same plane. Preferably they are connected to a disk 23, mounted rotatably 15 on the crank.

The motive fluid is conducted into the chamber formed by the crank-case and hereinafter termed the crank-chamber, through a bore 24 in the shaft 3. From this chamber, 20 a plurality of ducts 25 lead to the respective compression cylinders 15 and enter through the sides thereof. Each compression cylinder communicates with its associated power cylinder 14 by a duct 26, the position of 25 which is determined by the length and the stroke of the power piston 19. The ducts 26 are formed in chambers 26' shown in Fig. 3, which chambers may be cast with the end plate 17 common to the power cylinders. 30 That end of the duct communicating with the power cylinder, at 26'', is the induction port of this cylinder.

27 is the exhaust port, which is located slightly nearer to the outer or closed end of 35 the cylinder than is the induction port. The exhaust ports discharge rearwardly, that is to say, in directions opposite to that of the engine's revolution.

Describing now the mechanism for charging 40 the power cylinders at each reciprocation of their pistons, I prefer to construct said mechanism as follows: Upon the (fixed) shaft 3 is secured the hub 28 of a circular cam, which in the present instance 45 takes the form of a disk 29, whose plane is inclined from the perpendicular to the axis of its shaft. In the periphery of the cam-disk is turned a continuous ball-bearing groove 30. Mounted on this periphery is 50 what is in effect, an internally-grooved rotatable ring, though in practice it is desirable to make the same in three or more annular parts 31, 31, 32, as shown, which may be removed from and replaced upon 55 the cam-disk 29 and the interposed ring of balls 33. This ring, composed of the separable annular sections, is provided with a plurality of equally-spaced spherical knobs 34, held by stems of less diameter, as shown, 60 there being a knob for each of the compression cylinders 15. The pistons 35 of said cylinders are connected by their connecting-rods 36 with said knobs, respectively, by divided heads 37, thus forming ball-and-socket 65 joint connections. The piston-rods 36 are

connected to their pistons by cross-pins 39. It will be understood that when the cylinders are revolved, the cam ring 31-32 will be carried around upon the cam 29 and will describe a rotary wobbling movement. 70 The cam ring is propelled and the pivot-joints 39 of the piston rods are relieved of such strain as may be caused by the reaction of the cam-disk upon the ring, by means of radially-slotted guides 38 straddling said 75 rods. As shown in Fig. 1 these guides 38 are cast integral with the chamber 8 that encloses the cam. 38' indicates one face of the radial slot through which the uppermost piston-rod 36 extends. 80

In rotating upon the cam 29, any given point of the ring 31-32—for example, one of the ball-and-socket joints—will follow the periphery of said cam and in so moving will alternately approach and recede from the 85 proximate ends of the compression cylinders. It follows that each of the compression pistons 35 will thus be reciprocated once by each revolution of the engine. Owing to the circular form and inclined position of the cam 19, two opposite points thereof (marked *a* and *b*) are closer to the shaft, perpendicularly measured, than the two points at 90 degrees therefrom; hence as the piston-rods 36 are carried around they will be 90 radially oscillated, which motion is provided for by the piston pivots 39 and the ball-and-socket joints. The latter are necessary on account of the twisting or wobbling motion imparted to the cam ring by its rotation 95 upon the cam-disk. The piston-actuating mechanism above described will operate with a minimum degree of friction, and for that reason is preferred by me.

From the foregoing it will be seen that the 105 non-rotatable shaft 3, cam 29 and power crank 20 form reaction members to reciprocate the power and compression pistons.

In order to so time the reciprocations of the compression pistons that they do not exactly coincide with those of the power pistons, the compression cylinders are shown as staggered with respect to the power cylinders, and with this construction the cam-disk 29 will be set as shown, with its extreme points *a* and *b* practically in the same longitudinal plane as the axis of the crank 20, whereby the strokes of each compression piston will be properly timed with respect to the strokes of the associated power piston, as will hereinafter be fully described. It may be stated in this connection that the compression cylinders may be more nearly in radial register with the power cylinders—may in fact be arranged exactly opposite the same and the same timing effected by adjustment of the angular position of the cam-disk 29 with respect to the crank 20, to correspond with the altered positions of the compression cylinders. 125 130

It will be observed in Fig. 1 that the induction port 26" of the power cylinder 14 is not directly opposite the exhaust port 27, but is located slightly nearer to the exhaust end 5 of the cylinder. The power stroke of the piston carries its outer end beyond the exhaust port 27 and opens the induction port 26"; then the initial return movement of the piston closes first the induction port and 10 then the exhaust port. This operation, in connection with that of the compression piston 35, will now be described.

The gas or vapor being supplied through the bore 24 into the crank chamber 6, enters 15 the induction ports 25 of the compression cylinders 15. The engine is started by hand or otherwise until an explosion occurs in one of the power cylinders. During the initial 20 rotative motion of the engine, the compression piston 35, by its backward movement, creates a partial vacuum within its cylinder, as its duct 26 is at this time closed by the power piston 19. At the end of its backward stroke the piston 35 uncovers its induction 25 port 25 and a charge of gas rushes into the compression cylinder through this port. The piston 35 moves forward, first closing said port, then compressing the charge. In the meantime the power piston 19 has been 30 moving inwardly—*i. e.*, toward the exhaust end—and when near the end of its stroke uncovers the exhaust port 27 and, before the same is fully opened, starts to open the induction port 26". The compressed gas 35 rushes through said port into the power cylinder before the compression piston has quite completed its stroke; the power piston starts back, closing first the induction port and then the exhaust port, and there- 40 after compresses the charge. The ignition then occurs and the following combustion of the charge drives out the piston, as described hereinafter. During the very short interval when both ports 26" and 27 are partly open, 45 the incoming charge simply takes the place of the spent charge and assists in exhausting it, but is prevented from mixing therewith to any seriously detrimental extent by the deflector 41 carried by the piston.

50 The cycle of operations just described takes place in each pair of cylinders 14 15 in succession, and the reaction of the crank 20 upon the power piston-rods 21 causes the entire frame including the cylinders to 55 rotate around the shaft. It will be understood that each power cylinder will be charged with fresh gas under compression at each reciprocation, and every out stroke of the piston will therefore be a power stroke.

60 One of the principal advantages offered by this engine is the absence of valves and of the complex mechanism incidental thereto. Another advantage arises from the absence of a flywheel, none being required, owing 65 to the mass and hence the inertia of the re-

volving parts of the engine. Moreover, the construction described is very light in proportion to the power developed by the engine in operation.

Describing now the preferred ignition 70 system for this engine: the same comprises revoluble primary and secondary circuit-closers mounted on the engine, sparking plugs located one in each power cylinder in circuit with the secondary circuit-closers, 75 an induction coil having primary and secondary windings, and the usual battery and interrupter. The construction as shown in Fig. 1 is as follows: A metal ring 42, provided with a number of contact-lugs 43 80 equal in number to the power cylinders, is fixed upon the shaft 3 and insulated therefrom. A wire 44 connected to this ring forms a part of the primary circuit. Mounted on and electrically connected to 85 the adjacent rotary portion of the engine frame, is a wiper 45, adapted to form contact with each lug 43 in succession as the engine rotates. The circuit is through the frame of the engine, thence by a wire 46 to 90 the primary coil, interrupter, and battery (not shown). The circuit-closers for the secondary circuit consist of a circular series of equally-spaced contact-pieces 47, carried by and insulated from the crank-casing and 95 from each other, these contacts being also equal in number to the power cylinders. One terminal of each sparking plug 48 is connected by a wire 49 to the corresponding contact-piece 47; the other plug-terminal being connected to the frame of the engine. As the engine rotates, said contact-pieces pass in succession a fixed circuit-closing member 50 which is shown as held by and insulated from the standard 2. I prefer 100 that this member 50 be so adjusted as not to be actually contacted by the revolving pieces 47, but to stand very close thereto so that the air-gap will be exceedingly short. By this arrangement the wearing away of 105 the parts that would result from rubbing contacts, may be obviated.

The wires 51 and 52, from member 50 and frame respectively, form parts of the respective secondary circuits. The secondary 115 circuit-closers are so adjusted as to close the circuit through the sparkers of each cylinder at the instant when its piston arrives at the proper point of its compression stroke. The primary circuit is open, except during the 120 instants of sparking, in order to save battery power.

Either the wiper, or the contact ring, of the primary circuit may be adjusted circumferentially to properly advance or retard 125 the sparking point.

By the peculiar construction of the power cylinders and the arrangement of the sparking plugs therein, I obviate a trouble very common in gas engines, namely, interference 130

with sparking caused by the flooding of the plug contacts with lubricating oil, thrown thereon by the rapid strokes of the pistons. This exposure of the spark-terminals to the oil in ordinary engines is due to their position in the cylinders. My improvement consists in forming the ignition end of the cylinder with a laterally extending chamber, 53, the radially inner wall of which is 10 drilled and tapped to receive the sparking plug. Thus, when the plug is in position, as shown in Fig. 1, its contact points are out of alinement with the piston, and centrifugal force keeps the oil from flowing to the spark 15 plug.

The operation of the engine, including that of the igniting means, has already been described.

As hereinbefore stated, the construction 20 and arrangement of the compression cylinders may be varied from that shown in Fig. 1. For example the axes of said cylinders may be radial, as shown in Fig. 5. In this construction the compression-pistons are actuated from a second crank upon the crank-shaft, the crank-casing is enlarged to receive the two cranks, and the remainder of the construction is substantially the same as that shown in Fig. 1.

30 Referring to the drawing, 54 is the crank-shaft, through one end of which passes the bore 55 for the induction of the motive fluid into the crank chamber, from which the several ducts or ports 56 lead to the respective compression cylinders 57, entering about mid-length thereof. The compression-pistons 58 are actuated by a crank 59 of shaft 54, and the power pistons 60 in the power cylinders 61 are actuated by a crank 62.

40 The outer end of each compression cylinder 57 is connected to the adjacent power cylinder 61 by a duct 63 which terminates in the induction port 63' of the power cylinder and the eduction port of the compression cylinder, respectively. As also shown in Fig. 1, the exhaust port 64 is slightly offset longitudinally of the cylinder relatively to the induction port, for the reason hereinbefore described. The compression cylinders are here

50 set in angular alinement with the power cylinders, and for this reason it is desirable that the two cranks 59 and 62 be set, not exactly opposite or 180 degrees from each other; because, were the cranks opposite, the compression piston would start to return at the same time the associated power piston started on its return stroke, thus failing to effect the transfer of the full charge to the power cylinder. The correct timing of the compressing

60 strokes in the auxiliary cylinders may therefore be effected by setting the auxiliary crank 59 ahead of a position directly opposite the power crank 62, as indicated in Fig. 6; so as to effect a slightly following movement of the compression pistons. The oper-

ation of the engine is practically the same as described for the preferred form, and need not therefore be repeated.

In either construction, the power cylinders may be provided upon their sides and ends with parallel heat-radiating fins 65, set in their planes of revolution to cause unobstructed flow of air therebetween, thus keeping down the temperature of said cylinders without the use of the usual water-cooling system.

In the broader scope of the invention, the novel coöperation of associated power and compression cylinders set forth herein may be carried into effect in a construction in which the cylinders are stationary and a crank-shaft is actuated therefrom in the more usual manner.

I claim as my invention:

1. In a gas engine, a circular series of 85 power cylinders, a circular series of compression cylinders, a centrally disposed fixed reaction shaft, a piston in each of said several cylinders and operative connections between each piston and said shaft whereby said pistons are all caused to move in definite timed relation with each other, the compression cylinders being arranged with their axes substantially parallel and the exhaust ends of the several power cylinders arranged 90 adjacent to the compression ends of the respective corresponding compression cylinders, ducts connecting the several power cylinders with their corresponding compression cylinders and terminating in ports in 100 the power cylinders controlled by the respective pistons therein, said compression cylinders being each provided with an induction port, a source of gas supply common to all of the compression cylinders, and means for 105 igniting the charges in the power cylinders in regular succession.

2. In a gas engine, a circular series of power cylinders having their axes substantially radial to a common center and their exhaust ends radially inward, a circular series of associated compression cylinders having their axes parallel with each other and their compression ends respectively adjacent to the corresponding exhaust ends of the power cylinders, a piston in each of said several cylinders, a fixed reaction shaft centrally disposed relatively to the power cylinders and provided with a reaction crank, piston rod connections between said crank and the several pistons of the power cylinders, a reaction cam disk fixedly mounted opposite the ends of the several compression cylinders and operative piston rod connections between said cam disk and the several pistons of said compression cylinders, ducts controlled by the power pistons connecting the compression ends of the compression cylinders with the adjacent ends of the corresponding power cylinders, a gas supply 120

125

130

chamber common to all of the compression cylinders, and means for igniting the charges in the power cylinders in succession whereby the reaction of the power pistons upon said shaft imparts a relative rotation between said shaft and cylinders.

3. In a rotary gas-engine, a circular series of power cylinders, an associated circular series of compression cylinders, a piston in each of the respective cylinders, the exhaust end of each power cylinder being adjacent to the compression end of the associated compression cylinder, each associated power and compression cylinder being provided with a connecting duct, and each compression cylinder being provided with an induction port, an eccentrically disposed reaction crank to which the power pistons are operatively connected, a reaction cam mounted opposite the ends of the compression cylinders, an annular member mounted for rotation upon said cam, piston-rod connections between the compression pistons and said annular member, and suitable guides for said piston rods.

4. In a rotary gas-engine, a circular series of power cylinders, a circular series of associated compression cylinders, a piston in each of the respective cylinders, an eccentrically disposed reaction crank to which the power pistons are operatively connected, a circular cam-disk mounted opposite the ends of the compression cylinders, and inclined from a plane perpendicular to the axis of rotation of the engine, an annular member mounted to rotate upon said cam-disk, piston-rod connections between said annular member and the respective compression pistons, and suitable guides for said piston-rods.

5. In a rotary gas-engine, a circular series of power cylinders, a circular series of associated compression cylinders, a piston in each of the respective cylinders, an eccentrically disposed reaction crank to which the power pistons are operatively connected, a reaction-cam mounted opposite the ends of the compression cylinders, an annular member mounted for rotation upon said cam, a roller bearing between said annular member and cam, piston-rod connections between said annular member and the respective pistons of the compression cylinders, and suitable guides for said piston-rods.

6. A rotary gas-engine comprising an axial non-rotatable shaft, provided with a crank, a crank-casing revolvably mounted upon said shaft and having a gas chamber, a series of radially-disposed power cylinders carried upon said crank-casing, a compression-cylinder casting secured to the power

cylinders and comprising a series of compression cylinders the axes of which are parallel to said shaft, a second casing secured to the compression-cylinder casting and having a bearing upon the shaft, pistons in the cylinders, mechanism inclosed by said second casing for actuating the compression pistons, rods connecting the power pistons with said crank, there being a bore through a portion of the shaft, leading to the gas chamber formed by said crank-casing, and induction passages leading from said gas chamber to the respective compression cylinders, the power cylinders being provided with induction and exhaust ports, and the flow of gas into and from the power and compression cylinders being controlled by the pistons within said cylinders.

7. A rotary explosive engine comprising a plurality of revolvably mounted cylinders arranged in pairs, each pair comprising a power cylinder and a compression cylinder and pistons therein, a port in the side of each power cylinder, the compression end of the compression cylinder being arranged to communicate with the exhaust end of the power cylinder through said port, which is controlled and normally closed by said power piston, said compression cylinder being provided with an induction port opening through its side in the vicinity, but inside of the limit of the suction stroke of said compression piston, and controlled by said piston, a source of gas supply connecting with the induction ports of the compression cylinders, and suitable operative connections between the pistons of the pair of cylinders whereby they are made to move in timed relation.

8. A rotary engine comprising a plurality of revolvably mounted cylinders arranged in pairs, each pair comprising a power cylinder and piston therein and a compression cylinder and a piston therein each of said compression cylinders being provided with an intake, the compression end of the compression cylinder being arranged to communicate with the power cylinder through a controlled port normally closed by the piston of the power cylinder but timed to open when the power piston is in the vicinity of the end of its out or power stroke, and a centrally disposed crank casing constituting a gas supply chamber common to all the intakes of the compression cylinders.

MARTIN L. WILLIAMS.
